UNITED STATES PATENT OFFICE.

HOMER C. LA BATT, OF CHICAGO, ILLINOIS, ASSIGNOR TO WILLIAM J. HERRICK, OF CHICAGO, ILLINOIS.

SHEET-FEEDING MACHINE.

1,087,244.

Specification of Letters Patent.

Patented Feb. 17, 1914.

Application filed March 8, 1904. Serial No. 197,982.

To all whom it may concern:

Be it known that I, HOMER C. LA BATT, a citizen of the United States, residing at Chicago, in the county of Cook and State of Illinois, have invented certain new and useful Improvements in Sheet-Feeding Machines, of which the following is a specification.

This invention has reference to a machine for transmitting or delivering sheets of paper to a printing press, folding machine, ruling machine, or other machine employing or acting upon sheets of paper.

One of the objects of the invention is to provide a new and improved feeder which is so constructed and arranged that it may be easily moved into and out of operative position, and which, when the associated machine is provided with a feed board or table, may be located under the latter.

A further object of the invention is to provide a series of guides capable of adjustment in order to vary their position in accordance with the different requirements arising from the character of the paper.

Other objects will be apparent from the description and claims.

The invention consists of the combinations, arrangements, and organization of parts hereinafter particularly described and then pointed out in the claims.

In the accompanying drawings, which illustrate one embodiment of my invention, Figure 1 is a side elevation of the feeding machine of my invention shown in connection with the delivery end of a sheet separating machine and the rear end of a printing press, and illustrating the feeding machine in its operative position; Fig. 2 is a plan view of the same, with the printing press removed; Fig. 3 is a side elevation of the upper portion of the feeding machine, shown associated with a sheet separating machine and a printing press, but with its extensible section in its retracted inoperative position; Fig. 4 is a detail vertical longitudinal sectional view through the feeding machine showing the feeding tapes and rollers carrying the same, as well as the adjustable guides associated with the tapes; Fig. 5 is a detail sectional view illustrating the rack bar and pinion connection for advancing and retracting the extensible section of the feeding machine; and Fig. 6 is a detail view of means for holding the ex-

tensible section of the feeding machine against movement in its advanced or retracted positions.

The feeding machine may be supported or mounted in any suitable manner, as for example as illustrated, and comprises a pair of slide rails C, C which are carried by brackets c bolted to the side members a of the frame of a sheet separating machine A. The forward ends of the rails C are supported by blocks c' carried by brackets c' fastened to the frame of the printing press B. The side rails C are so disposed that the forward ends of the same extend under the rear end of the feed board or table b' of the printing press and serve to support the extensible section of the machine. This extensible section in the present embodiment of the invention comprises a pair of side bars D, movable through or in guide apertures formed in blocks or boxes d fixed to the side rails C and also through or in aligned apertures formed in the blocks c'. The bars D are tied together or connected at their rear or free ends by a cross bar d' which is bolted at each end to blocks d', d' fixed to the ends of the bars D.

The feeding machine is provided with suitable means for delivering the sheets to the cylinder b of the printing press. In the present embodiment of the invention such means comprise a series of endless tapes or bands carried by each section. As shown in Fig. 2, the tapes c' pass over or around the feeding off roll a' of the sheet feeding machine and a roller c', which is mounted on a shaft c' journaled at its ends in the block c'. These tapes c' are spaced apart any suitable distance and carry the sheets to the tapes d' of the extensible section, the latter tapes passing around the roller c' and alternating with the tapes c', being carried at their forward ends by a roller d' which is journaled at its ends in the blocks d', d'.

The tapes may be driven in any suitable manner, as through the medium of the feeding off roll a', which is driven in any suitable manner as through the medium of the gear a' and the tapes c' turning the roller c' the tapes d' are driven at the same surface speed as the tapes c'.

From the foregoing it will be understood that as each sheet is delivered to the tapes c', such sheet will be carried and delivered to the tapes d' and by them presented to the

press gages. In Fig. 1 the extensible section of the machine is shown in its operative position so as to deliver sheets to the printing press, the usual hinged table section b^2 of the hand feed board b' being swung upwardly out of the way to permit the delivery end of the extensible section to occupy the position normally occupied by the said hinged section. When it is desired to feed the sheets to the press by hand the extensible section is retracted to the position shown in Fig. 3 and the foldable section b' of the printing press feed board is folded down to the position shown in the latter figure.

Any suitable means may be provided for advancing and retracting the extensible section of the feeding machine. In the present construction the bars D are made in the form 20 of rack bars, with the teeth of which mesh pinions c^6 , fixed upon a cross shaft c^7 journaled in bearings c^8 depending from the guide boxes or blocks d , as shown in Fig. 5. A hand wheel c^9 is keyed to the shaft, and 25 by turning such hand wheel the bars D may be advanced or retracted at will.

Any suitable means may be employed for holding the extensible section against movement in its operative position. In the present instance one of the rack bars D is provided with a notch or depression d^6 near the front end adapted to coöperate with a latch, as shown in Fig. 6, where d^7 indicates a bolt movable through an aperture in the block d and engaging the depression d^6 . The bolt is fixed to a flat spring d^8 attached to the block d and having its free end bent outwardly to permit of the spring being readily grasped to withdraw the bolt. It is obvious 40 that when the extensible section is moved into the position shown in Fig. 1 the parts will co-act to lock the extensible section in such position, as shown in Fig. 6; if it is desired to lock the extensible section in its 45 retracted position a second notch may be provided in the bar D adapted to coöperate with the bolt d^7 when the extensible section is retracted. Tensioning devices, such as E, may be provided for maintaining the tapes 50 sufficiently taut, and these tensioning devices are carried by a cross bar e supported by brackets fixed on the side rails C, and may be adjusted laterally on the bar e in case of lateral adjustment of the tapes in order 55 that they may be in the proper position to coöperate with the tapes, being held in their adjusted position by set screws e' .

Associated with and carried by the feeding machine at its rear end is a registering device which is designed to square or align the front or advancing edge of each sheet. This front register may be of any suitable construction adapted to the attainment of the desired ends. In the present

embodiment of the invention it consists of 65 a blade F which is periodically and automatically lowered into the path of the advancing sheet of paper and is then raised after the front edge of the paper has been aligned with the gages of the press. This 70 blade in its operative position occupies a vertical position in the path of the paper as clearly shown in Fig. 3, and is provided 75 at its upper edge with a flange f , which not only serves to strengthen the blade, but also provides means by which the ends of the blade are bolted to a pair of arms f' fixed to a rock shaft f^2 , one end of which is journaled in an ear f^3 of the support d^3 while the other end is journaled in an extension f^4 of the 80 block d^2 , as seen in Figs. 1, 2, and 3. Fixed to the shaft f^2 is a crank arm f^5 to which is pivoted one end of a link f^6 , pivoted at the other end to a slide f^7 , moving in a guide or way formed in the upper face of the block 85 d^2 , as shown in Fig. 2. Attached to the slide f^7 is one end of a connecting rod f^8 extending parallel with the side rails C and connected at its other end to a slide f^9 mounted and moving in a way formed in the block c' 90 at that side of the machine, as seen in Fig. 2. Pivoted to the said block c' is an arm f^{10} provided at its upper end with a slot which receives a stud f^{11} projecting from the slide f^9 . The arm f^{10} is designed to be actuated 95 by a cam, which may take the form of a disk g , having a radial enlargement or cam face g' , fixed on a shaft g^2 , journaled at its ends in the blocks or boxes c' . Preferably the arm f^{10} is provided with an anti-friction 100 roller f^{13} in the plane of movement of the disk g so as to be engaged at the proper time by the cam g' to move the connecting rod f^8 forwardly and through the medium of the connecting mechanism rock the shaft f^2 and 105 lower the blade into the path of the advancing sheet. When the cam portion of the disk passes out of engagement with the anti-friction roller f^{13} , the blade is raised in any suitable manner, as by means of springs f^{14} , 110 which are coiled about the rock shaft f^2 as shown in Fig. 2 and each of which is anchored at one end to one of the arms f' while the other end is attached to the supports for the shaft so as to normally exert a tendency 115 to elevate the blade F. The shaft g^2 may be driven in any preferred manner, as by a bevel gear g^3 which meshes with a gear g^4 , fixed on a vertical shaft g^5 , journaled in 120 suitably supported bearings g^6 . The shaft g^5 has motion communicated to it through the medium of bevel gearing g^7 which derives motion from the associated machine, such as the printing press. It is to be understood, however, that the arrangement of the connections for driving the various operative parts of the machine is not material and may be varied as desired.

The sheets of paper pass from the rear end of the tapes d^4 to a delivery device which in the present form consists of fingers h , which, when the extensible section 5 is in its operative position, occupy the position and take the place of the delivery fingers on the hinged section of the press hand feed board. The fingers h are mounted upon brackets h' , carried by the cross 10 bar d' , and adjustably secured thereto by means of set screws h^2 , as seen in Fig. 4. The blade F of the front gage when in active position stands in advance of the ends 15 of the fingers h in the path of the moving sheets so that the sheets passing over the fingers will necessarily engage the blade. In order to prevent the sheets of paper from passing the ends of the fingers h and slipping under the blade, certain of the fingers, 20 at suitable intervals, are provided with spring extensions h^3 fixed to the said fingers and projecting in advance of the latter in such position that the blade F rests thereon when in its depressed position, thereby 25 rendering it impossible for a sheet to slip on the fingers and under the blade and the spring extensions. Two of the spring extensions h^3 are extended sufficiently to project over the press cylinder so as to co-act 30 with the press gages which in their depressed position rests upon said extensions. It is obvious that instead of the fingers h the delivery device may be in the form of a plate, as in Fig. 4, which may extend substantially the width of the machine. 35

Associated with the feeder is suitable mechanism for registering the sides of the sheets of the paper so as to place the same in predetermined position for proper alignment with the co-operating part of the associated machine, such as the form of a printing press, for example. This side registering device, designated in general by the letter S , comprises generally a gripping device 40 adapted to engage the side edge of the sheet and move the same laterally to adjust it into its predetermined position. The side register is supported in any suitable manner preferably at a suitable distance from the rear of the machine as, for example, by the cross bar d' , and is so positioned upon such bar as to grip the paper according to the width of the stock employed.

The gripper comprises a body mounted on the bar d' and having a passage through which the bar d' extends. The body is intended to be adjustably mounted on the rod d'' to provide for adjustment of the side register and to permit its being readily moved and wet to prevent accidental displacement thereof in the operation of the register, and is provided with a pair of jaws s^6, s^7 , suitably spaced and connected at their outer edges by a web against which the paper is

squeezed. The jaw s^6 is preferably extended 65 inwardly in order to provide a relatively large table to receive one edge of the sheets from the tapes, while the jaw s^7 may be relatively short. The jaws s^6, s^7 are so disposed that the upper face of the jaw s^6 is 70 in the plane of the tapes d^4 and in order to insure the sheet entering between the jaws they are arranged divergently or flared outwardly toward the front end of the machine. 75

The rod s^7 to which the side register S is connected by which it is reciprocated is controlled by any suitable mechanism. In the construction illustrated the block d^3 is provided with a suitable horizontal way in 80 which is mounted a slide p' provided with a pin or stud p^2 co-operating with a cam as hereinafter explained. The rod s^7 may be attached directly to the slide p' , but in order to provide for a simple and precise adjustment of the side register the said rod passes through an aperture in the support d^3 and is attached to an arm p^3 connected to a screw p^4 having threaded adjustment in the outer end of the slide p' . Mounted on the 90 upper face of the block d^3 in a suitable way p^5 is a slide p^6 provided with a cam slot p^9 disposed so as to receive the pin or stud p^2 of the slide p' .

Motion may be communicated to the cam 95 plate or slide p^6 through the medium of any suitable mechanism. As shown in the present construction the cam plate p^8 is attached to one end of a rod p^{10} , connected at its other end to a slide p^{11} , mounted in a way formed 100 in the upper face of one of the blocks c' . Fixed to the adjacent end of the cross shaft g^2 is a cam disk p^{12} provided with a depression p^{13} and designed to actuate the rod p^{10} in one direction for communicating motion to the side register. This is accomplished through the medium of an arm p^{14} (Fig. 3), pivotally mounted at its lower end on the associated block c' , and provided at its upper end with slot p^{15} in which plays 110 a stud p^{16} , fixed to the slide p^{11} . The arm p^{14} is preferably provided with an anti-friction roller p^{17} disposed in the plane of movement of the cam in order to reduce the friction of the parts. 115

The cam p^{12} is designed to move the cam slide p^8 outwardly to return the side register after its inward movement, while a spring p^{18} advances or moves the register inwardly after each impulse of the cam. 120 The spring p^{18} is shown as an expansion spring coiled about a stem p^{19} fixed to a plate p^{20} on the support d^3 and passing freely through an aperture in a lug p^{21} on the slide, so as to react between the said plate and the lug. The spring holds the arm p^{14} in operative relation to the cam. 125 The action of the side register is designed

to be rapidly accomplished and to this end the recess p^{13} extends only a short distance in the cam which extends nearly the whole of the periphery of the disk to hold the register normally retracted and stationary. When the recess in the cam comes into alignment with the arm, the spring p^{18} moves the register operating rod s^{17} inwardly and the operation is then completed by the anti-friction roller p^{17} passing upon the cam p^{12} again so as to return the rod outwardly.

In the operation of the side register S , the sheet carried by the tapes d^4 enters between the jaws in position to be engaged by the web preferably near the end of the inward movement of the carrier, it being obvious, however, that the sheets will be engaged and registered if upon the lower jaw at any point within the range of movement of the carrier. The sheet is first engaged at its front edge by the front gage F in the manner heretofore described. The front gage is then raised out of the path of the sheet which is then carried by the tapes. As soon as the sheet has been arrested by the press gages, the recess in the cam comes in register with the anti-friction roller p^{17} , permitting the spring p^{18} to expand and move the cam slide p^8 rearwardly, so as to move the rod s^{17} in the direction of the feathered arrow in Fig. 2 which thrusts the web of the register against the edge of the sheet between the jaws so as to move the sheet laterally and inwardly. The sheet is released and the press gages are moved out of the way and the sheet is taken by the grippers b^3 of the press cylinder, in the usual manner.

Only one register S need be employed in order that the impression on both sides of the sheets may register with each other, in case the sheets are cut with accuracy so that the side edges are parallel. Under other conditions and in order to accommodate the machine to variations in stock, etc., a second register S' is employed and located at the opposite side of the machine so as to register the sheets from the same side edge for the second impression as for the first impression.

To secure the best results it is desirable to have the two side registers grip the sheet at the same point between its ends and the register S' is therefore preferably mounted on the cross bar d' and located at the side of the machine opposite to the register S . The register S' is of the same character, construction and operation as the register S , and is operated by a rod t , connected thereto in a manner corresponding to the rod s^{17} with the register S , and which is connected to a slide t' similar to the slide p' and disposed parallel with the slide p' in a way formed in the upper face of the block d^3 .

It is actuated by a pin entering a cam slot t^2 formed in the cam slide p^8 , such cam slot t^2 being disposed at an angle and reversely to the slot p' so that the same mechanism for operating the register S may be employed for operating the register S' . As these registers are designed to be operated independently of each other, only one of them operating at any time, the connecting pin p^2 is designed to be used with either slide, being removably inserted therein. Assuming that the sheets are to be alined by the register S at one edge in making the impression on one side, the pin p^2 is placed on the slide p' , and the register operated in the manner already described. When the sheets have been run through the press they are turned over so that the same side edges before adjacent the register S are now disposed adjacent the register S' . The pin p^2 is then removed from the slide p' throwing the register S out of operation and is inserted in the slide t' thereby operating the register S' so that the sheets will be registered from the same side edges for the impression upon the other face and insure the impression upon both faces being in exact register.

In order to permit of the advance and retraction of the extensible section of the machine the connecting rod p^{10} instead of being permanently fixed to the slide p^{11} extends through apertured lugs or ears p^{22} on the said slide and is provided at its end with a shoulder p^{23} and at a suitable point at the opposite end of the slide with a nut p^{24} which screws upon a threaded portion p^{26} of the rod as shown in Fig. 2, thereby detachably connecting the rod to the slide. When it is desired to move the extensible section rearwardly the nut p^{24} is unscrewed, permitting the rod p^{10} to slide through the apertured lugs p^{22} in the slide, as shown in Fig. 3. The same means are employed for detachably connecting the connecting rod f^8 to the slide f^9 to permit of movement of the extensible section, as shown in Fig. 2.

Carried by suitable brackets or rods r , which may be bolted at suitable intervals along and transversely to the sections of the frame of the machine, are guides located just along the plane of the tapes c^3 and d^4 to hold the sheets carried by the tapes against the latter and to prevent the sheets from buckling or curling up at the edges. These guides consist of straight rods or wires r' having their ends bent inwardly, as shown in Fig. 4, to avoid interference with the paper. These guides are designed to be adjusted vertically and laterally in order to cooperate with paper of varying thickness, flexibility and width. To provide for this vertical and lateral adjustment, the guides r' are carried by vertical arms r^2 which pass

through apertures in blocks r^3 provided with set screws r^4 engaging the arms to hold the latter in adjusted position. The blocks r^3 are provided with ears r^5 which engage or 5 embrace the cross rods r and set screws r^6 passing through the ears fix the blocks in any desired position but permit of the blocks being moved along the rods to adjust the guides laterally. The guides r' may be attached 10 to the arms r^2 in any suitable manner. In the present instance I have shown each of the arms provided with section r^7 between which and the arms r^2 the wires are clamped by thumb nuts r^8 . Any number of the 15 guides desired may be employed, and they may be located directly over the tapes or intermediate of the tapes. When the extensible section is to be advanced or retracted in the manner heretofore described the nuts r^8 are loosened so that the guides will slide 20 freely in their supporting arms. The rear ends of the guides r' of the extensible section preferably extend over the delivery device of the feeder, such as the plate h^4 (Fig. 25 4). These guides coöperate with the delivery device and form a narrow throat terminating adjacent the gage F and preventing any buckling or curling of the sheets by their impact on the gage.

30 In the operation of making the press ready for clear and accurate printing the pressman must take a number of proofs and then make such alterations in the tympan as are suggested by the successive proofs until a clear 35 and uniform impression is obtained, and it is, therefore, necessary to repeatedly get at the tympan before the "make ready" is complete. The hinged section of the feed board permits ready access to the press cylinder to 40 remove and replace the tympan for this purpose, and by locating the automatic feeder below the board it is when in its retracted position entirely out of the way of the pressman during these preliminary operations. 45 and in such relative location that the extensible section may then be readily moved into its operative position.

The present machine is particularly adapted 50 for feeding sheets from a sheet separating and feeding machine to a paper handling machine of any suitable character, such as a printing press or the like, but it is to be understood that the sheets may, if desired, be fed to the feeding machine by hand and 55 that the character of the associated machine may be of any preferred type and mode of operation.

I make no claim in the present application 60 to the side registering devices herein shown as the same is reserved for and forms part of the subject-matter of my co-pending application filed June 27, 1904, Serial Number 214,238; and I make no claim herein to the front stop mechanism herein shown as the

same is reserved for and forms the subject- 65 matter of my divisional application filed May 31, 1904, Serial Number 210,401 issued as Patent Number 986,726, dated March 14, 1911.

Having described my invention what I 70 claim as new and desire to secure by Letters Patent is—

1. In combination with a paper handling machine, such as a printing press, provided with a hand feed board having a movable 75 delivery section, of an extensible feeder located under the board and adapted to be reciprocated into the space normally occupied by the delivery section of the board and into coöperative relation with the said ma- 80 chine when the movable section is thrown out of the way.

2. In combination with a paper handling machine, such as a printing press, provided with a hand feed board having a hinged de- 85 livery section, of a feeder having an extensible section adapted to be reciprocated into the space normally occupied by the delivery section of the board and under the board and into coöperative relation with the said ma- 90 chine when the delivery section is swung out of the way.

3. In combination with a paper handling machine, such as a printing press, having a cylinder and a hand feed board provided 95 with a hinged delivery section normally coöperative with the cylinder, of an automatic feeder provided with an extensible delivery section adapted to be reciprocated into the space normally occupied by the delivery sec- 100 tion of the board and into coöperative relation with the cylinder when the hinged section is swung out of the way.

4. In combination with a paper handling machine, such as a printing press, having a 105 cylinder, a hand feed board provided with a hinged delivery section normally coöperating with the cylinder, of an automatic feeder comprising a stationary and a sliding section provided with carrying tapes, the ex- 110 tensible section being adjustable under the board and into coöperative relation with the cylinder when the hinged section is swung upwardly out of the way.

5. In a mechanism for feeding sheets to 115 a paper handling machine, in combination, a stationary section, a movable delivery section slidably carried by the stationary section, the delivery section being stationary when in operative position, and endless carrying tapes mounted on the sections to carry the sheets over the stationary section to and over the movable section.

6. In a mechanism for feeding sheets to a 125 paper handling machine, in combination, a stationary section, a movable delivery section slidably mounted on and supported by the stationary section, endless carrying tapes

carried by the two sections to carry the sheets over the stationary section to and over the movable section, and means for sliding the movable section.

5. 7. In a mechanism for feeding sheets to a paper handling machine, in combination, a stationary section comprising a pair of bars, rollers journaled between the bars, endless tapes running over the rollers, a movable delivery section comprising a pair of rack bars slidably supported by the stationary bars, a shaft provided with pinions meshing with the rack bars, and endless tapes carried by the movable section to receive the sheets from the stationary section.

8. In a machine of the class described, in combination, a stationary section comprising a pair of stationary bars having guide blocks, rollers journaled between the ends of the bars, endless tapes running over the rollers, a movable section comprising a pair of rack bars mounted in the guide blocks, a roller journaled between the front ends of the rack bars, endless tapes running over the latter roller and the roller of the adjacent end of the stationary section, and an operating shaft journaled on the guide blocks and having pinions meshing with the rack bars.

9. In a machine of the class described, in combination, a stationary section comprising a pair of stationary bars adapted to be fixed to the delivery end of the sheet separating and feeding machine, and having a pair of guide blocks fixed to each bar, rollers journaled between the ends of the rods and carrying endless tapes, a slidable section comprising a pair of rack bars movable on the guide blocks, a roller journaled between the rear ends of the rack bars, tapes running over the latter roller and the roller at the adjacent end of the stationary section, a shaft journaled on one pair of the guide blocks and having pinions meshing with the rack bars, and a spring dog carried by one of the guide blocks and engaging the associated rack bar to hold the slidable section against movement.

10. In a sheet feeding machine, in combination with the frame consisting of a stationary and adjustable section and provided with carrying tapes, of the cross bars carried by each section, brackets mounted on and adjustable along the bars, vertically adjust-

able arms attached to the brackets, and guide rods carried by the arms.

11. In a sheet feeding machine, in combination with the carrying tapes, of a delivery device located at the rear ends of the tapes, a front gage thereon, and guides extending substantially the length of the tapes and located over the tapes and the delivery device.

12. In a sheet feeding machine, in combination with the carrying tapes, of a delivery device located at the rear ends of the tapes, a front gage thereon extending when in active position in the path of the sheets over the delivery device, and guides located above and extending substantially the length of the tapes and terminating adjacent the gage.

13. In a sheet feeding machine, in combination with the stationary and the extensible sections provided with carrying tapes, of the registering device carried by the extensible section, a slide supported by the stationary section, means for reciprocating the slide and a rod detachably connected to the slide and for actuating the registering device.

14. In a sheet feeding machine, in combination with the stationary and extensible sections provided with carrying tapes, of the registering device carried by the extensible section, a block fixed to the movable section, a slide moving on the block, a cam operated arm for moving the slide in one direction, a spring for moving the slide in the opposite direction and a rod detachably connected to the slide for actuating the registering device.

15. In a sheet feeding machine, in combination with the stationary and extensible sections provided with carrying tapes, of the registering device and the gage carried by the extensible section, slides mounted on the stationary section, means for moving the slides, and connecting rods detachably connected to the slides for communicating motion from the slides to the said registering device and the gage.

In testimony whereof I affix my signature in presence of two witnesses.
